BLASTING CAP ASSEMBLY

Lylburn S. Cagle, Bunker Hill, Ill., assignor to
 Olin Industries, Inc., East Alton, Ill., a corpora-
 tion of Delaware

Application August 20, 1949, Serial No. 111,435

1 Claim. (Cl. 102—28)

1

This invention relates to electrically fired blasting caps and in particular to the provision of improved means whereby accidental firing of a cap through untimely contact of the lead wires with a source of electric current will be prevented.

In order to facilitate connection of electrically fired blasting caps with a source of electric current it is customary to have a short length of insulation removed from the ends of the wires leading from the caps. In order to avoid accidental ignition of such caps, it has also been common practice to provide a means for short circuiting the lead wires by connecting the bared ends of the wires until firing is to take place. Such means for short circuiting the lead wires is ordinarily referred to as a shunt. One means for shunting the lead wires which has been used in the trade for a number of years is that shown and described in the patent to Barab, U. S. 1,895,438 dated January 31, 1933. This comprises an eyelet of relatively soft metal having a peripheral groove in which the bared lead wires are clamped to provide the necessary short circuit. Insofar as short circuiting the lead wires is concerned, such a metal eyelet assembly has proven entirely satisfactory. However, occasional difficulty is encountered in removing the metal eyelet from the lead wires when it is desired to fire the cap and on occasions the operator's fingers have been scratched or cut, introducing considerable hazard into the operation. Furthermore, in clamping the bared lead wires about the eyelet body or in the removal of the eyelet therefrom, the wires occasionally are so bent or nicked that they break when an attempt is subsequently made to make connection with a source of electric current. This is not desirable since the operator must then take time to remove more insulation from the remaining lead wire or the blasting cap will not fire.

It is also common practice to identify each blasting cap as to size, type, etc. by means of an identification tag. Such identification tags have been fastened to the blasting cap or its lead wires in a number of ways, among which are to thread one of the lead wires through an eyelet hole near the end of the tag or by passing an auxiliary wire through the hole and then twisting the auxiliary wire about the lead wires. In all such instances the installation of the shunts and tags require two separate operations and likewise their removal requires two separate and sometimes difficult operations when the blasting cap is put to use.

It is an object of this invention therefore to

2

provide means for short circuiting the lead wires and means for identifying the blasting caps which permit a more economical assembly and facilitate safe handling in the operations preceding firing. Another object of the invention is to reduce the number of operating steps necessary to attach the identification tag and short circuit the lead wires. Another object is to provide the lead wires of an electrically fired blasting cap with a shunt which is efficient and yet may be removed from the lead wires by the operator without any hazard such as scratching or cutting his fingers. Still another object is to provide the lead wires of an electrically fired blasting cap with a shunt which upon assembly or removal does not tend to nick or otherwise weaken the bared ends of the lead wires. A still further object is to provide a shunt and identification tag both of which may be removed from the blasting cap lead wires in a single operation by merely pulling on the tag.

The foregoing objects and advantages as well as others which may become apparent from the detail description hereinafter, are accomplished 25 in accordance with this invention by providing a blasting cap assembly in which a single eyelet both short circuits the wires leading from the blasting cap and attaches a tag thereto which may be used for identification. Inadvertent firing of the blasting cap is accordingly prevented 30 and identification is accomplished by attaching the identification tag to the uninsulated free ends of the lead wires with an eyelet- or grommet-shaped member, the rim of the eyelet hole of the tag and the uninsulated ends of the lead wires being disposed within the peripheral groove of the member. By thus combining the identification tag and the short circuiting member, two operations formerly necessary can be accomplished in one with a resulting reduction in 35 manufacturing cost. Furthermore, the identification tag can be used as a handle or grip to readily remove the short circuiting member from the lead wires without mutilation of the operator's fingers and without deleteriously bending or nicking the bared lead wires.

Having indicated in the foregoing in a general way the nature and substance of this invention, there follows a more detailed description of a 50 preferred embodiment thereof with reference to the accompanying drawing in which:

Figure 1 is a perspective view illustrating a blasting cap assembly embodying this invention.

Figure 2 is an enlarged perspective view illustrating the metallic shunt member, and Figure 3

is a perspective view of an identification tag, prior to assembly with the wires leading from the blasting cap.

Figure 4 is a back view of the tag, eyelet, and wire assembly illustrated in Figure 1, and

Figure 5 is an enlarged sectional view of the tag, eyelet and lead wire assembly taken at AA of Figure 1.

Referring first to Figure 1, a casing 1 of any suitable material, as for example copper, such as is usual in blasting caps, contains the explosive. The insulated lead wires 2 at one end are connected to a fusible filament which is positioned in the igniter material within the casing 1 in the conventional manner. The igniter material as is customary is adapted to be fired electrically through the medium of the fusible filament connected across the lead wires 2. The lead wires 2 externally of the casing 1 are insulated except for a short length from their free ends as indicated at 4. The uninsulated free end portions of the lead wires permit connection to an electric circuit when the blasting cap is to be fired.

The shunt member, illustrated in Figure 2, may be formed of any suitable material such as copper, iron, etc., has a substantially circular or cylindrical body portion 5 about which the uninsulated lead wires 4 are wrapped, and a shoulder 7 which prevents the lead wires from slipping off one end of the body portion 5. The body portion 5 is then inserted through the eyelet hole shown at 8 of the identification tag 3, Figure 3. If the tag 3 is formed of relatively thin or weak material the rim of the eyelet hole 8 may be reinforced to prevent the shunt 5 from tearing out of the tag. Such reinforcement may be accomplished by applying an additional layer of reinforcing material on the eyelet end of the tag as illustrated in U. S. Patent 1,658,328, issued February 7, 1928, to Eastman, or in any other suitable manner. The end 6 of the shunt member, Figure 2, may be slotted or otherwise weakened for easy deformation and is then crimped as illustrated in Figure 4 to form a slotted shoulder holding the tag 3 and lead wires 4 firmly between the shoulder 7 and deformed end 6 but not so tightly as to prevent removal of the shunt by pulling thereon when it is desired to fire the cap. As thus assembled the shunt member will preferably have the form of a ring having a peripheral groove with the tag and wires clamped therein and may be of any suitable or desired diameter. If desired the shunt member may be solid rather than of ring form or for example polygonal-shaped or the like, but a ring form is preferred from the standpoint of ease of assembly. Referring to Figure 5 it may be seen that the shunt is a rivet-like member holding the tag 3 and uninsulated lead wires 4 between the shoulders 6 and 7 thereof. The uninsulated lead wires 4 may be wrapped either only partially or completely around the body 5 of the shunt and the shunt is preferably positioned near the end of the insulation on the lead wires. Likewise the end portion 6 of the shunt may be fashioned as a continuous shoulder, as at 7, or the shoulder 7 may be fashioned with slots as at end 6, so that both shoulders may be either continuous or slotted. Likewise, the identi-

fication tag 3 may be placed adjacent the continuous shoulder 7 and the lead wires 4 adjacent the slotted shoulder 6. It is preferred, however, to have the lead wires adjacent a smooth shoulder such as at 7 to minimize the possibility of nicking or otherwise deforming the lead wires 4 in the clamping or removal operations. Thus, the shunt member and its assembly may be substantially identical with that described in the Barab patent U. S. 1,895,438 with the exception that the body portion 5 should be sufficiently long to accommodate both the lead wires 4 and the tag 3.

As will be apparent from the foregoing specific embodiment, the identification tag is attached and the lead wires short circuited in a single clamping operation. When it is desired to use the blasting cap both the identification tag and shunt can be removed simultaneously in one operation, without deleterious deformation of the uninsulated ends of the lead wires or injuring the hands of the operator, merely by grasping the identification tag firmly between the thumb and forefinger and pulling. It is contemplated this invention can be utilized even with blasting caps not requiring an identification tag, since the tag in such instances, whether printed, or otherwise marked, or plain, can still be used as a flap or tab for safely removing the shunt from the blasting cap lead wires. It is to be understood that the embodiment of the present invention as shown and described is only illustrative and that many changes may be made therein without departing from the spirit and scope of the invention as set forth in the following claim.

Having thus described the invention what is claimed and desired to secure by Letters Patent is:

In combination with a blasting cap adapted for electrical firing and provided with lead wires having uninsulated end portions, a tag having an eyelet hole, and a shunt member with a peripheral groove extending through said hole, said uninsulated end portions of the lead wires being wrapped around said shunt member and disposed in said groove so as to effect a contact between them per se, the ends of said shunt member being flared to provide shoulders thereon with the rim of the hole in said tag and said wrapped end portions of the lead wires being held in position by compression between said shoulders, said tag having a portion extended from said shunt member as a handle for manually pulling said shunt member from said wires.
